UNITED STATES PATENT OFFICE.

OSCAR GLOVER, OF LOUISVILLE, KENTUCKY.

FUEL-ECONOMIZER FOR INTERNAL-COMBUSTION ENGINES.

1,165,871.

Specification of Letters Patent. Patented Dec. 28, 1915.

Application filed August 25, 1915. Serial No. 47,334.

To all whom it may concern:

Be it known that I, OSCAR GLOVER, a citizen of the United States, residing at Louisville, in the county of Jefferson and State 5 of Kentucky, have invented certain new and useful Improvements in Fuel-Economizers for Internal-Combustion Engines, of which the following is a specification.

The device which is the subject matter 10 of the present application for patent is an attachment for motor vehicle engines of the internal-combustion type, and has for its object to reduce the amount of fuel consumed by the engine, and to obtain a maximum speed and power with a minimum 15 quantity of fuel.

The invention also has for its object to provide a device which prevents or minimizes carbon deposits on the intake and 20 exhaust valves of the engine.

The objects stated are attained by means of a novel combination and arrangement of parts to be hereinafter described and claimed, reference being had to the accompanying drawing, in which—

Figure 1 is an elevation of the device applied to the engine; Fig. 2 is an elevation of the device, partly in section, and Fig. 3 is another view of the device also partly in 30 section.

Referring specifically to the drawing, 5 denotes the engine of an automobile or other motor vehicle, the engine being of the ordinary internal-combustion type and having an intake manifold 6 to which the carbureter 35 7 is connected. To the intake manifold, between the carbureter and the fuel inlet of the engine cylinders is connected an auxiliary air supply comprising a pipe 8 leading from a chamber 9 which is cylindrical in shape and closed at its ends by caps 10 and 11, respectively. This chamber has a series of air-inlet apertures 12 located near the top thereof, and it is also provided with 40 a valved outlet, a valve 13 being connected to the bottom cap 11. The delivery pipe 8 is connected to this valve, and intermediate its ends, said pipe is coiled around the exhaust pipe 14 of the engine, as indicated at 45 15, which is for a purpose to be presently described.

Alongside the chamber 9 is mounted an oil reservoir 16, which may be an ordinary glass oil cup having a delivery pipe 17 which 55 is connected to the chamber to discharge thereinto, near the bottom. The flow of oil

from the reservoir is controlled by a valve 18 having a stem 19 extending from the top of the reservoir, and on the latter is mounted a support 20 for a valve operating lever 21 fulcrumed intermediate its ends to the support, as indicated at 22. One end of the lever is connected to the valve stem 19, and its other end is connected to an operating rod 23, the lever having an aperture through 60 which the rod loosely passes. Above the lever, the rod carries an abutment 24, which latter may be a nut, provided with a lock nut 25, the rod being screw-threaded to receive the same. Thus, when the rod is drawn 65 down, the lever is swung to open the valve 18. A valve-closing spring 26 is also provided. On the lower end of the rod is an abutment 27, which latter may also be a nut 70 screwed on the rod.

The valve 13 may be an ordinary turning plug having a stem 28 projecting from the valve casing, and provided with a stop pin 29 coöperating with shoulders 30 on the valve casing, to limit the rotation of the 75 valve plug.

To the valve stem 28 is connected a laterally extending arm 31 having at its outer end a fork 32, and connected to an actuating rod 33 extending to a point within easy 80 reach of the driver.

The normal suction of the engine 5, while running, takes in air at the inlets 12, the amount being regulated by the valve 13. The abutment 27 will be adjusted so that 90 when a certain amount of air is supplied by turning the valve plug, the fork 32 will strike said abutment and draw the rod 23 down, thereby opening the oil valve 18 as hereinbefore described. Oil now flows into 95 the chamber 9 and is sucked out of the same with the air, and in its passage through the coil 15, the mixture of oil and air is heated before it enters the engine cylinders. The oil enters the cylinders in the form of a fine 100 spray, which lubricates the intake and exhaust valves, and prevents the accumulation of carbon on the same and the stems thereof, the carbon being discharged with the exhaust. It has also been found that excessive 105 heating of the cylinders is prevented. The additional air supply, heated before its delivery to the engine, results in a saving of fuel, and it has been found that the speed of the engine is increased without increasing the fuel supply.

By pouring a few drops of gasoline into

the chamber 9, the starting of the engine is facilitated, which is desirable, especially in cold weather.

The oil valve 18 can be opened at any time 5 to supply oil, by pressing down on the lever 21, and by means of the abutment 27 the proportion of oil and air may be varied to obtain the best result. Any good grade of lubricating oil may be used to supply the 10 reservoir 16.

The preferred embodiment of the invention has been described and illustrated, but it will be evident that various changes and modifications in the structural details 15 closed may be made without departure from the spirit and scope of the invention as claimed hereinafter.

I claim:

1. The combination with an internal-com-
20 bustion engine; of a chamber having an air inlet and an outlet connected to the intake of the engine between the carbureter and the fuel inlet of the engine cylinder, a lubricant reservoir connected to the chamber, a valve 25 controlling the outlet of the chamber, a valve controlling the lubricant supply from the reservoir to the chamber, and an opera-
tive connection between said valves.

2. The combination with an internal-com-
30 bustion engine; of a chamber having an air

inlet and an outlet connected to the intake of the engine between the carbureter and the fuel inlet of the engine cylinder, a lubricant reservoir connected to the chamber, a valve 35 controlling the outlet of the chamber, a valve controlling the lubricant supply from the reservoir to the chamber, an operating rod connected to the last-mentioned valve and having an abutment, and an operating stem for the first-mentioned valve adapted 40 to be intercepted by the abutment.

3. The combination with an internal-com-
bustion engine; of a chamber having an air inlet and an outlet connected to the intake 45 of the engine between the carbureter and the fuel inlet of the engine cylinder, a lubricant reservoir connected to the chamber, a valve controlling the outlet of the chamber, a valve controlling the lubricant supply from the reservoir to the chamber, an operating rod connected to the last-mentioned valve and having an adjustable abutment, and an operating stem for the first-mentioned valve adapted 50 to be intercepted by the abutment.

In testimony whereof I affix my signature 55 in the presence of two witnesses.

OSCAR GLOVER.

Witnesses:

CARRIE HEISER,
JOHN IRICK.
